UNITED STATES PATENT OFFICE.

RUSSELL B. PERKINS, OF MERIDEN, CONNECTICUT, ASSIGNOR TO EDW. MILLER & CO., OF SAME PLACE.

CHANDELIER.

SPECIFICATION forming part of Letters Patent No. 284,890, dated September 11, 1883.

Application filed July 5, 1883. (No model.)

To all whom it may concern:

Be it known that I, RUSSELL B. PERKINS, of Meriden, in the county of New Haven and State of Connecticut, have invented a new Improvement in Chandeliers; and I do hereby declare the following, when taken in connection with accompanying drawings and the letters of reference marked thereon, to be a full, clear, and exact description of the same, and which said drawings constitute part of this specification, and represent, in—

Figure 1, a top view; Fig. 2, a section on line $x x$ of Fig. 1; Fig. 3, a sectional side view of the central part of a chandelier, showing the 15 arm-holding device in place.

This invention relates to an improvement in devices for securing the arms in lamp-chandeliers. These arms are made from tubing, or with a cylindrical shank which will enter a 20 center-piece, and in which center-piece the arms are secured.

The object of my invention is to construct the center-piece in a cheap and durable manner, and so that the arms may be securely held; 25 and it consists in the construction as herein-after described, and more particularly recited in the claim.

The center-piece, which has the usual position in the chandelier, is composed of a disk, 30 A, having a vertical flange, B, around its edge, through which flange, at the proper points, holes a are made, through which the shank b of the arm will pass and usually fit. Within this center is a flange, C, in which holes d are 35 made, corresponding to the holes in the outer flange, and into which the inner end of the shank will enter. In each of the shanks a horizontal groove, e , is made on the upper side, near the inner end.

D is a disk placed over the center-piece, and 40 upon the under side of which is a circular flange, f , corresponding to the groove e in the shanks, and so that when the flange f is entered into the groove, as seen in Fig. 2, the arms are held in place. This disk D is secured by several screws, E, introduced through it into the other disk, or vice versa, or the inner flange, C, may be screw-threaded upon its outside, as at h , and the interior of the flange f correspondingly threaded, and so that the 45 disk D may be screwed onto the interior flange, C, until the flange f bears properly in the grooves of the shank of the respective arms. This makes a very simple construction, easily 50 understood, and not liable to derangement.

I do not wish to be understood as claiming, broadly, the construction and arrangement of a holder within the body of the chandelier to grasp the arms inserted therein, as such I am aware is not new.

I claim—

The herein-described improvement in centers for chandeliers, consisting of the disk A, constructed with the outer and inner flanges, B C, each of said flanges constructed with 65 openings to receive the shank of the respective arms, combined with the disk D, constructed with a flange, f , upon its under side to set into a corresponding groove at the end of the respective arms, and means, substantially such as described, to secure said two disks together, substantially as described.

RUSSELL B. PERKINS.
